AIR OUTLET DEVICE

Friedrich Honerkamp, Franz J. Kurth, and Maurice Serre, New York, N. Y., assignors to Anemostat Corporation of America, a corporation of Delaware

Application November 5, 1940, Serial No. 364,464

12 Claims.

(Cl. 98—40)

This invention relates to ventilating apparatus, and has particular reference to improvements in outlet devices for the delivery of fresh or conditioned air into rooms or other enclosures.

Usually draftless delivery of fresh or conditioned air into rooms or other enclosures is desired. In some instances, however, it is equally or even more desirable to have fresh or conditioned air delivered into a room or other enclosure in the form of a jet or blast. For example, in the case of air sickness of a person in the cabin of an aircraft, sea sickness of a person in a room of a ship, or nausea of a person in a railway car or other land vehicle, it is desirable, in order to overcome or alleviate the sickness or nausea, to direct a jet or blast of fresh or conditioned air toward the person affected. Also, in the case of an aircraft, ship or other conveyance travelling from a cool climate or atmosphere to a warm or hot climate or atmosphere it may be desirable for reasons of comfort to passengers or operators to have fresh or conditioned air delivered to the cabin or rooms of the aircraft, ship or other conveyance in the form of a jet or blast instead of draftlessly or in a diffused manner. Accordingly, the primary object of the present invention is to provide an air outlet device embodying a construction whereby it may readily be adjusted to effect delivery of fresh or treated air into a cabin, room or other enclosure either in a diffused, substantially draftless manner, or in the form of a jet or blast, or, if desired, partly in diffused form and partly in the form of a jet or blast. Also in this connection another object of the invention is to provide for additional adjustments of the device whereby an air jet or blast may conveniently be delivered in various different directions and in different intensities from the device.

Another object of the invention is to provide an air outlet device embodying provision for the adjustments mentioned and which, at the same time, is of simple, inexpensive construction, strong, sturdy and unlikely to get out of order and which is thoroughly reliable and efficient in operation.

With the foregoing and other objects in view, which will become more fully apparent as the nature of the invention is better understood, the same consists in an air outlet device embodying the novel features of construction, combination and arrangement of parts as will be hereinafter more fully described, illustrated in the accompanying drawings and defined in the appended claims.

In the accompanying drawings, wherein like characters of reference denote corresponding parts in related views:

Figure 1 is a central, longitudinal section through an air outlet device constructed in accordance with one practical embodiment of the invention, the device being shown adjusted for the diffused delivery of air therefrom.

Figure 2 is a view similar to Fig. 1 showing the device adjusted for the delivery of air therefrom in the form of a jet or blast.

Figure 3 is a side elevation of the device as shown in Fig. 2.

Figure 4 is a cross section on the line 4—4 of Fig. 3.

Figures 5 and 6 are sections similar to Fig. 4 showing the air jet or blast orifice of the device closed and fully open, respectively.

Figure 7 is a central, longitudinal section through an alternative form of the device having a position of adjustment to effect diffused delivery of air therefrom.

Figure 8 is a view similar to Fig. 7 showing the device adjusted to effect delivery of air therefrom in the form of a jet or blast; and

Figure 9 is a front end view of the air jet or blast delivery tube of the device shown in Figs. 7 and 8.

For convenience and definiteness in describing the present device it will be assumed that the same is used as a ceiling outlet. The device may, however, be used as a side wall outlet. It is to be understood, therefore, that the terms used to describe the device as a ceiling outlet apply

equally as well to the device should the same be installed as a side wall outlet.

Referring now to the drawings in detail, first with particular reference to the embodiment of the invention illustrated in Figs. 1 to 6, 10 designates the neck of the device which may be of any suitable length and of circular or any other suitable shape in cross section, and 11 designates a flaring member constituting a bottom continuation of said neck, either as an integral part thereof or as a part separate therefrom and joined thereto in any suitable manner.

Of smaller diameter than the neck 10 and disposed therein, preferably concentrically with respect thereto, is a cylindrical sleeve 12, while 50 constituting a bottom continuation of said sleeve, either as an integral part thereof or as a part separate therefrom and joined thereto in any suitable manner, is a flaring member 13 which is spaced inwardly from the flaring member 11. 55 Thus, the neck 10 and the sleeve 12 define there-

between an annular air supply passageway designated as *a*, while the flaring members *11* and *13* define therebetween a flaring air expansion passageway *b*, also of annular form, which is open at its ends and which, at its upper end, is in air receiving communication with the annular air supply passageway *a*.

Preferably the flaring passageway *b* is divided into two or more separate flaring passageways by one or more open-ended, hollow flaring members *14* interposed between the flaring members *11* and *13*. This, however, is not essential. Neither is it essential that the flaring member *13* constitute a bottom continuation of the sleeve *12*. On the contrary, said flaring member *13* may extend from the side of said sleeve *12*, in which event said sleeve may extend downwardly any suitable distance beyond the point of junction of the upper end of the flaring member *13* therewith. Moreover, while the drawings illustrate the lower ends of the flaring members *11*, *13* and *14* as being disposed in a common plane, this likewise is not essential, as the lower ends of said members may be disposed in various other relationships to each other.

In the present instance a frusto-conical filler block *15* is illustrated as being disposed within the flaring member *13* to, in effect, extend the sleeve *12* downwardly to the lower end of said flaring member *13*, while the sleeve *12*, the flaring members *13* and *14* and said filler block are illustrated as being mounted in assembly with each other and with the neck *10* and the flaring member *11* by means of screws *16* extending through the flaring members *11*, *14* and *13* and threaded into said filler block, spacing elements *17* being interposed between said flaring members. However, the filler block *15* is not essential, particularly if the sleeve *12* is extended downwardly beyond the point of junction of the flaring member *13* therewith, and in that case may be dispensed with if desired. Moreover, the sleeve *12* and the flaring member *13*, as well as the flaring member or members *14*, if same are used, may be mounted in assembly with the neck *10* and the flaring member *11* in any other suitable manner.

Mounted in the sleeve *12* for longitudinal sliding movement and for rotation with respect thereto is a tube *18* which is open at its top and at or near its top is provided with an outwardly extending flange *19* constituting a valve for controlling flow of air into the annular passageway *a* from a duct *20* with which the neck *10* is connected. In this connection it will be noted that the upper end of the neck *10* is covered by a rubber ring *21* against which the flange *19* is designed to seat to close the passageway *a*, as illustrated in Fig. 2 of the drawings. However, said ring is not essential. Neither is it essential that the flange *19* cooperate with the top of the neck *10* to control flow of air from the duct *20* to the passageway *a*. On the contrary, the flange *19* obviously may cooperate with the bottom wall of the duct *20*.

At its lower end the tube *18* is provided with an inwardly extending flange *22* upon which seats the bottom of a cup-like valve member *23* which snugly fits the bottom portion of said tube and is rotatable therein.

In the side of the tube *18* near the lower end thereof is an air blast outlet port *24*, while in the side of the valve member *23* is a port *25* for alignment with and disalignment from the port *24* by rotation of said valve member *23* relative to said tube *18*.

The flange *22* defines in the bottom of the tube *18* a central opening, and in this opening is disposed an upwardly offset central portion of a disk *26* the marginal portion of which underlies the flange *22*. Against the bottom of the disk *26* is disposed a knob or handle *27*, while extending downwardly through the bottom wall of the valve member *23* and the central portion of the disk *26* and threaded into said knob or handle are screws *28* which serve to connect said valve member, disk and knob or handle securely together. A swivel connection thus is provided between the tube *18* and the valve member *23* whereby the latter is maintained rotatably mounted in the lower end portion of said tube for convenient rotation therein by means of the handle *27*. Moreover, since the handle *27* is immovable longitudinally with respect to the tube *18*, said handle constitutes a convenient means for use in shifting said tube *18* longitudinally with respect to the sleeve *12*.

Carried by the valve member *23* at one side of the port *25* therein is a lug *29* which extends outwardly through the port *24* in the tube *18* for cooperation with stops constituted by the edges of said tube defining the sides of the port *24* therein. Thus, the lug *29* in conjunction with said stops limits rotation of the valve member *23* to an amount just sufficient to fully open and close the port *24*. It will be apparent, therefore, that when the valve member *23* is rotated in a direction to align the ports *24* and *25*, that is to say, to open the port *24*, any further rotation of said valve member in that direction after alinement of said ports will result in the tube *18* being rotated with said valve member. Likewise it will be apparent that when the valve member *23* is rotated in the opposite direction to disalign the ports *24* and *25* and thereby close the port *24*, any further rotation of said valve member in said opposite direction after closing of said port *24* will result in the tube *18* being rotated therewith in said opposite direction. Manifestly, therefore, the handle *27* is adapted for use not only to rotate the valve member *23* relative to the tube *18* to open and close the port *24* and to shift said tube *18* longitudinally relative to the sleeve *12*, but also to rotate said tube *18* relative to the sleeve *12* to rotatably adjust the port *24* relative to the device.

The disk *26* is of a diameter such that its marginal portion underlies the inner portion of the filler block *15*. Thus, upward movement or retraction of the tube *18* is limited by engagement of the marginal portion of said disk with the stop constituted by the bottom face of said filler block *15*. On the other hand, downward movement or projection of the tube *18* is, of course, limited by engagement of the flange *19* with the ring *21* or with the bottom wall of the duct *20*, as the case may be. In this connection the length of the sleeve *12* and of the port *24* and the permissible amount of longitudinal movement of the tube *18* are such that when said tube is fully retracted, as shown in Fig. 1, the port *24* is completely closed by the sleeve *12* and the filler block *15* regardless of the position of the valve member *23* relative to said tube, and when said tube is fully projected, as shown in Figs. 2 and 3, said port *24* is disposed completely below the bottom of the filler block *15*. Thus it is apparent that when the tube *18* is fully retracted no air may flow therefrom through the port *24* and all air supplied to the device from the duct *20* must enter the device through the annular passageway *a* and be delivered from the device through the

70
75

flaring passageway *b*. On the other hand, it is apparent that when the tube *18* is fully projected the annular air passageway *a* is closed against flow of any air thereto from the duct *20* and all air delivered from the device must pass through the tube *18* and its port *24*. Alternatively, in intermediate positions of longitudinal adjustment of the tube *18*, part of the supplied air obviously may flow through the passageways *a* and *b* and the remaining part may flow through said tube *18* and its port *24* under the control of the valve member *23*. By rotatably adjusting the valve member *23* relative to the tube *18* the amount of air which may flow through the port *24* may be regulated, while by rotatably adjusting said tube *18* the port *24* may be positioned to direct the air delivered therethrough in any direction laterally with respect to the device.

Preferably, but not necessarily, the valve member *23* is provided with suitable means for deflecting supplied air, passing through said tube, toward the port *24*, said means comprising, for example, either a filler block *30* disposed in said valve member and having an upper face inclined downwardly toward said port, as shown, or, alternatively, simply a deflector plate mounted in said valve member in any suitable manner.

Air flowing through the port *24* obviously is delivered from the device in the form of a jet or blast. On the other hand, due to the annular flaring nature of the passageway *b*, and especially to the dividing of said passageway into a plurality of separate flaring passageways if one or more of the flaring members *14* are used, air flowing through said passageway *b* is delivered from the device in diffused, substantially draftless form.

Any suitable means may be provided to hold the valve member *23* in different rotatably adjusted positions relative to the tube *18*, and any other suitable means may be provided for holding said tube *18* in different positions of longitudinal and rotative adjustment relative to the sleeve *12*. However, practical means for these purposes may comprise a ring *31* of felt or other friction material interposed between the flange *22* and the disk *26*, and a sleeve *32* of felt or other suitable friction material interposed between the sleeve *12* and the tube *18*. The frictional resistance to rotation of the valve member *23* offered by the ring *31* is less than the frictional resistance to rotation of the tube *18* offered by the sleeve *32*. Consequently, the valve member *23* may be rotatably adjusted to vary the effective area of the port *24* without disturbing any given position of rotative adjustment of the tube *18*. Of course, to effect rotative adjustment of the tube *18* in one direction or the other it first is necessary to rotate the valve member *23* to a position fully closing or fully opening the port *24*, depending upon the direction in which it is desired to rotatably adjust the tube *18*. Thereafter, the valve member *23* may be rotatably adjusted relative to the tube *18* to vary the effective area of the port *24*.

Recapitulating, it is apparent that the present outlet device provides for the diffused, substantially draftless delivery therefrom of all supplied air flowing therethrough, or for the jet or blast delivery therefrom in any one of numerous different directions of all supplied air flowing therethrough, or for the delivery of part of the supplied air in diffused, substantially draftless form and of the remaining part of the supplied air in the form of a jet or blast; also, for regulation

of the amount of air delivered either in diffused or jet blast form.

The device illustrated in Figs. 7 to 9 of the drawings is, generally speaking, of the same construction and mode of operation as the device illustrated in Figs. 1 to 6, except in respect to the valve means for controlling flow of air through the tube *18a* which corresponds to the tube *18* of the Figs. 1 to 6 construction.

According to the Figs. 7 to 9 form of the invention the tube *18a* is provided with a port *24a* opening through the side and also through the bottom thereof, and with a valve, designated generally as *33*, for regulating the amount of air flowing through said port and its direction of flow therefrom.

The valve *33* comprises a plate *34* hinged at one end to the bottom of the tube *18a*, as indicated at *35*, for swinging movement between a horizontal position, as shown in Fig. 7, in which it closes the portion of the port *24a* in the bottom of said tube, and any one of a number of other positions in which it extends downwardly from the bottom of said tube *18a* at an inclination thereto and to a greater or lesser extent opens the said portion of the port *24a* in the bottom of said tube *18a*. Moreover, said valve includes side walls or wings *36* which serve to close the sides of the space between the plate *34* and the bottom of the tube *18a* when said plate is swung downwardly from its position shown in Fig. 7 so that air flowing from the tube *18a* through the port *24a* is confined between said side walls or wings and thereby is caused to be delivered in jet or blast form from said tube. In this connection one or more air deflector plates *37* may connect the side walls or wings *36* in spaced, parallel or substantially parallel relationship to the plate *34* to divide the air delivered from the tube *18a* into two or more separate streams, but the plates *37* are not essential and their use is optional. In any event, downward swinging movement of the plate *34* from its position shown in Fig. 7 increases the effective area of the port *24a* and determines the angle at which air will be delivered downwardly and outwardly from said port.

Obviously the port *24a* may be confined to the bottom of the tube *18a* and need not be formed in part in the side of said tube. It is preferred, however, to have said port formed in part in the side of said tube in order to provide for delivery of air laterally from said tube in certain instances. If a portion of the port *24a* is in the side of the tube *18a* such portion of said port will not be closed by the plate *34* when said plate is in its closed position illustrated in Fig. 7. In that case some air might undesirably leak through the tube *18a*, even when said tube is retracted and the portion of the port *24a* in the side thereof is closed by the sleeve *12a*, if the tube *18a* should, when retracted, be in open communication at its upper end with the air supply duct *20a*. Accordingly, a fixed valve element *38* of rubber or other suitable material may be provided to close the upper end of the tube *18a* when said tube is retracted. This valve element *38*, if provided, may be supported, for example, upon the top wall of the duct *20*, as shown, or in any other suitable manner.

The plate *34* is provided with a suitable handle *27a* for adjusting same relative to the tube *18a* and also for longitudinally and rotatably adjusting said tube.

Without further description it is thought that the features and advantages of the invention will

be readily apparent to those skilled in the art, and it will of course be understood that changes in the form, proportion and minor details of construction may be resorted to, without departing from the spirit of the invention and scope of the appended claims.

We claim:

1. An air outlet device for connection with an air supply duct, said device comprising an open-ended sleeve, a tube closely fitting said sleeve and disposed for communication with the duct when the device is operatively connected with the duct, means providing an open-ended air passageway outwardly of said sleeve disposed for communication with the duct when the device is operatively connected to the duct, said tube having an air outlet opening and being projectable and retractable and rotatable relative to said sleeve to dispose said air outlet opening for delivery of air from different points and in different directions relative to the device, means operable by projection of said tube to close said passageway and by retraction of said tube to open said passageway, a valve carried by said tube and adjustable relative thereto to regulate flow of air through said opening, a handle on said valve disposed in front of the front end of said tube to adjust said valve relative to said tube to regulate flow of air through said air outlet opening, and means whereby said handle is operable, through said valve, to project and retract and rotate said tube relative to said sleeve.

2. An air outlet device for connection with an air supply duct, said device comprising an open-ended sleeve, a tube closely fitting said sleeve and disposed for communication with said duct when the device is operatively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, and a valve element within said tube coaxial therewith and axially rotatable relative thereto, to vary the effective area of said side opening.

3. An air outlet device for connection with an air supply duct, said device comprising an open-ended sleeve, a tube closely fitting said sleeve and disposed for communication with the duct when the device is operatively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, said tube also being rotatable relative to said sleeve to dispose said air outlet opening in desired angular relationship to said sleeve, a valve element within said tube coaxial therewith and axially rotatable relative thereto to vary the effective area of said side opening, and means limiting rotation of said valve element relative to said tube to render said valve element effective to rotate said tube.

4. An air outlet device for connection with an air supply duct, said device comprising an open-ended sleeve, a tube closely fitting said sleeve and disposed for communication with the duct when the device is operatively connected with said duct, means providing an open-ended air passageway outwardly of said sleeve disposed to be in communication with the duct when the device is op-

eratively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, means carried by said tube to close said passageway when the tube is projected and to open said passageway when the tube is retracted, and a valve within said tube, coaxial therewith and axially rotatable relative thereto to vary the effective area of said side opening.

5. An air outlet device for connection with an air supply duct, said device comprising an open-ended sleeve, a tube closely fitting said sleeve and disposed for communication with the duct when the device is operatively connected with said duct, means providing an open-ended air passageway outwardly of said sleeve disposed for communication with the duct when the device is operatively connected with said duct, said tube being projectable and retractable and rotatable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, and to be disposed in desired angular position relative to the device by rotation of said tube, means operable by projection of said tube to close said passageway and by retraction of said tube to open said passageway, valve means carried by said tube and adjustable with respect thereto to vary the effective area of said air outlet opening, a handle on said valve means exposed at the forward end of the device for manipulating said valve means, and means whereby said handle is operable through said valve to rotatably and longitudinally adjust said tube relative to said sleeve.

6. An air outlet device for connection with an air supply duct, said device comprising an open-ended sleeve, a tube closely fitting said sleeve and disposed for communication with the duct when the device is operatively connected thereto, said tube having an air outlet opening and being projectable and retractable and rotatable relative to said sleeve to dispose said air outlet opening for delivery of air from different points and in different directions relative to the device, valve means for regulating flow of air through said opening, means defining an air delivery passageway around said sleeve for communication with the duct when the device is operatively connected thereto, means whereby projection of said tube denies communication between the duct and said passageway and whereby retraction of said tube establishes communication between said duct and said passageway, and fixed means with which said tube cooperates when retracted to deny communication between said duct and said tube.

7. An air outlet device for connection with an air supply duct, said device comprising an open-ended sleeve, a tube closely fitting said sleeve and disposed for communication with the duct when the device is operatively connected thereto, said tube having an air outlet opening and being projectable and retractable and rotatable relative to said sleeve to dispose said air outlet opening for delivery of air from different points and in different directions relative to the device, means defining an air delivery passageway around said sleeve for communication with the duct when the device is operatively connected thereto, means

whereby projection of said tube denies communication between said duct and said passageway and whereby retraction of said tube establishes communication between said duct and said passageway, and a valve for regulating flow of air through the air outlet opening in said tube, said valve comprising a plate pivoted to said tube and swingable outwardly therefrom to increase the effective area of said opening, and wings on the sides of said plates to close the sides of the space between said plate and the tube when the plate is swung outwardly from the tube.

8. An air outlet device for connection with an air supply duct, said device comprising an open-ended sleeve, a tube closely fitting said sleeve and disposed for communication with said duct when the device is operatively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, a valve element within said tube coaxial therewith and axially rotatable relative thereto, to vary the effective area of said side opening, and air deflector means carried by said valve element for deflecting air laterally through said opening.

9. An air outlet device for connection with an air supply duct, said device comprising an open-ended sleeve, a tube closely fitting said sleeve and disposed for communication with said duct when the device is operatively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, a valve element within said tube coaxial therewith and axially rotatable relative thereto, to vary the effective area of said side opening, and means providing within said valve an air deflecting surface inclined relative to said valve toward said opening to deflect air laterally through said opening.

10. An air outlet device for connection with an air supply duct, said device comprising an open-ended sleeve, a tube closely fitting said sleeve and disposed for communication with said duct when

the device is operatively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered, by projection of the tube relative to said sleeve, and air deflector means carried by said tube for deflecting air laterally through said opening.

11. An air outlet device for connection with an air supply duct, said device comprising an open-ended sleeve, a tube closely fitting said sleeve and disposed for communication with said duct when the device is operatively connected with said duct, said tube being projectable and retractable relative to said sleeve and having a side air outlet opening to be closed by said sleeve when the tube is in a retracted position relative to said sleeve and to be disposed in advance of the forward end of said sleeve and thereby uncovered by projection of the tube relative to said sleeve, and valve means within said tube for regulating flow of air through said side opening in said tube.

12. An air outlet device for connection with an air supply duct, said device comprising an open-ended sleeve, a tube closely fitting said sleeve and having an open rear end to afford communication between said tube and the duct when the device is operatively connected to the duct, said tube having an air outlet opening, means including a valve carried by said tube for regulating flow of air through said opening, said valve being adjustable relative to said tube to a position completely denying flow of air through said outlet opening and to different positions to vary the effective area of said opening, said tube being projectable and retractable relative to said sleeve so that air may be delivered at different points longitudinally relative to the device, and a handle fixed to said valve for adjusting the same relative to said tube and also for operation, through said valve, to project and retract said tube relative to said sleeve, said handle being disposed in front of the front end of said valve and also in front of the front ends of said sleeve and tube for ready access in all positions of adjustment of said valve and said tube.
